FOREIGN PATENT DOCUMENTS

WO WO 2016/139372 9/2016

Primary Examiner — Kelley A Donnelly(74) *Attorney, Agent, or Firm* — Eric Karich; Karich & Associates(57) **CLAIM**

The ornamental design for a zip tie organizer, as shown and described.

DESCRIPTION

FIG. 1 is a perspective view of a zip tie organizer, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof illustrating zip ties, rubber bands, and pliers operably positioned on the zip tie organizer.

The broken line showing of zip ties, rubber bands, and pliers depict portions of the article that form no part of the claimed design.

1 Claim, 6 Drawing Sheets(56)
